(Cl. D64—11)

FIG. 1

FIG.2

FIG.3

FIG. 1 is a front perspective view of a calculator embodying our new design;

FIG. 2 is a front perspective view of a modified form thereof, embodying a full keyboard in lieu of the 10-key keyboard and totalizing window shown in FIG. 1; and

FIG. 3 is a rear perspective view thereof.

The essential features of our design reside in the portions shown in solid lines.

We claim:

The ornamental design for a calculator, substantially as shown and described.
